UNITED STATES PATENT OFFICE.

CHARLES H. SHUTTLEWORTH, OF CORUNNA, MICHIGAN, ASSIGNOR OF ONE-HALF TO FRANK F. HOYER, OF SAME PLACE.

CAR-COUPING.

SPECIFICATION forming part of Letters Patent No. 448,304, dated March 17, 1891.

Application filed July 11, 1890. Serial No. 358,365. (No model.)

To all whom it may concern:

Be it known that I, CHARLES H. SHUTTLEWORTH, a citizen of the United States, residing at Corunna, county of Shiawassee, State 5 of Michigan, have invented a certain new and useful Improvement in Car-Couplers; and I declare the following to be a full, clear, and exact description of the invention, such as will enable others skilled in the art to which it pertains to make and use the same, reference being had to the accompanying drawings, which form a part of this specification.

In the drawings, Figure 1 is a view of the under side of a car, illustrating my coupler and draw-head. Fig. 2 is an end elevation. Fig. 3 is a vertical section illustrating the construction. Fig. 4 is a detail view of the draw-head. Fig. 5 is a detail view of one form of the coupling-pin. Fig. 6 is a side elevation 20 of another form. Fig. 7 is a cross-section of the latter.

In carrying out the invention, A represents the body of the car, and B the draw-head.

I will first describe the construction of the 25 coupler. The end of the draw-head is slotted vertically, as shown at b, and in this vertical slot is pivoted the link or coupler C. Because of the draw-heads being slotted entirely through the link when not in use can drop down 30 out of the way, as shown at C', Fig. 3. These links or couplers C C' are provided with a cross-piece c on the end, thus forming a T-end. The upper surface of each draw-head is shaped, as shown in Fig. 3, with lugs or projections b' having their inner faces slightly recessed, whereby the cross-piece on the adjacent coupler can engage behind the lugs or projections, and thus couple the two cars 35 firmly together.

40 It will be observed in Fig. 2 that the link or coupler is thrown up. When so thrown up and the two draw-heads come together, the backward movement or yielding of the draw-head drops the links and it engages with the adjacent draw-head before the two can separate, thus making an automatic coupler. So, 45 also, by this construction, as will be observed in Fig. 3, should the cars be of unequal height the coupler will still be operative, because of 50 the vertical slot—that is, the link or coupler will engage the adjacent draw-head, no mat-

ter whether the latter is above or below the level of the draw-head in which the link or coupler is pivoted. In order that the link may be raised without the necessity of going 55 between the cars, I provide the crank-shaft or lever D, having the arms d adjacent to the edge of the car. The shaft or pivot of the link also has a crank-arm c' engaged to the crank portion d' of the crank-shaft by the 60 chain d². Now by throwing up the arms of the crank shaft the link is raised and rod D', extending to the top of the car, is also engaged to the crank portion d', whereby the link may be raised from the top of the car. 65

In order that the ordinary link-and-pin coupler may be used where a car provided with my coupler must be coupled with an old-style car, I provide the draw-head with a horizontal opening b², whereby the ordinary link 70 may be inserted, and I groove both sides of the vertical slot, as shown at b³, whereby a pin may be inserted into the link. This pin is of a peculiar shape, being formed with a T shape at both ends, as illustrated in Fig. 75 5. Now, as will be seen, by inserting the link into the vertical slot, and then passing the pin down through the grooves b³ until the lower end of the pin has passed out of the slot, the pin can be drawn forward with the upper end 80 resting on the top of the draw-head, and the coupler thus locked firmly together until the pin has been drawn back to the grooves, when it may be removed; or, if desired, the pin may be shaped as shown in Figs. 6 and 7, and in 85 that case the pin would rest in the grooves all the time. This latter form of pin makes an exceedingly strong one, since the flanges extending in the four directions brace each other and reduce the liability of breakage to 90 a minimum.

I will now describe the construction of the draw-head. The draw-head is provided with a slot or opening E, and a shaft or spindle F extends lengthwise thereof. Engaged to the 95 frame-work of the car is a cross-piece G, having the block g, which fits into the slot or opening E of the draw-head, the shaft or spindle F passing through an opening g' in said block and playing freely therein. A spiral 100 spring H embraces the shaft F, one end bearing against the draw-head, while the other

bears against the block *g*, thus keeping the draw-head in its outer or advanced position, except when pressure is brought to bear upon the outer end, when it will yield slightly 5 against the spring, but will be returned as soon as the pressure is removed. It will thus be observed that the entire pressure of the load is brought upon the cross-piece *G*, and as this can be firmly engaged and made a 10 part of the frame-work the draw-head can be made extremely strong and substantial, and yet will yield easily to a shock incident to cars coming together.

Among the many advantages of this style 15 of coupler and draw-head are that the link can be easily raised without the necessity of going between the cars, that two cars of unequal height may be readily coupled together by either link, that a car provided with my 20 coupler can be engaged to the ordinary link-and-pin coupler, that the draw-head will easily give when sudden pressure is brought to bear on its end, and that when not in use either of the links may be dropped down out 25 of the way because of the vertical slot through the draw-head.

What I claim is—

1. In a car coupler, the combination, with a vertically-slotted draw-head, a link pivoted therein having at its end a cross-bar, and projections on the draw-head for engagement with the link of the adjacent car, of a crank-arm *c'*, crank-shaft *D*, provided with crank *d'*, said crank *d'* and crank-arm *c'* suitably connected with each other, and means connected with the crank *d'* for operating the coupler from the top of the car, substantially as described. 30 35

2. In a car-coupler, a draw-head provided with a vertical slot, a link pivoted therein, and link-engaging projections on the upper surface of the draw-head, said draw-head also having a horizontal groove for the reception of an ordinary link and a vertical slot for the reception of an ordinary pin, substantially as 40 45 described.

In testimony whereof I sign this specification in the presence of two witnesses.

CHARLES H. SHUTTLEWORTH.
